FUEL FEEDER

Earle V. Francis, Columbus, Ohio, assignor to
The Jeffrey Manufacturing Company, a cor-
poration of Ohio

Application July 28, 1933, Serial No. 682,680

14 Claims. (Cl. 221—134)

By virtue of its relative economy as compared with other fuel burning operations, the use of solid fuel in powdered form in both domestic and industrial heating installations offers advantages 5 of a substantial character, especially in installations of an automatic or semi-automatic operation.

In domestic heating systems, especially where the supply of fuel to the firebox of a furnace or 10 boiler is automatically controlled, the use of pulverized coal over other forms of fuel available for such automatic systems is increasing in popularity by virtue of the comparatively low cost of the fuel and economy in the operation of such 15 systems.

The present invention deals with a form of apparatus usable in connection with a system employed for burning pulverized solid fuel, such as powdered coal, and the invention relates more 20 especially to the provision of a storage hopper for the powdered fuel in which hopper is incorporated mechanism for properly feeding the fuel into the burner instrumentalities employed for the actual combustion of the coal. One of the 25 principal problems involved in installations of this character lies in the proper rate of feed of fuel to the burner, so that neither an excess nor deficiency of fuel supply will result.

One of the objects of the present invention 30 therefore is the provision of fuel storage and feeding instrumentalities which will deliver the fuel at the proper rate of speed for efficient combustion, and which will maintain the stored body of fuel in condition to be delivered in an efficient 35 manner to the burner.

A further object of the invention which may be mentioned specifically is the provision of improved feeding instrumentalities by means of which the fuel may be transferred from the main 40 stored body to the outlet in regulated quantities for discharge to the burner, these being provided also with simplified means for adjusting the regulating mechanism by which this transfer is effected.

45 Other objects and advantages will become apparent as the description proceeds.

The present invention may be more readily understood by reference to the accompanying drawings in which

50 Fig. 1 is an elevational view of an apparatus embracing the features of the present invention.

Fig. 2 is an enlarged fragmentary elevation of the apparatus of Fig. 1, showing, in dotted lines, mechanism for agitating and feeding the powdered material contained in the apparatus, to-

gether with the arrangement of drive instrumentalities therefor.

Fig. 3 is a sectional view of a portion of the drive mechanism the view being taken on the line 3—3 of Fig. 2.

Fig. 4 is a vertical sectional view through the apparatus of Fig. 1, the view being taken on a vertical axis looking in the direction of the arrows of line 4—4 of Fig. 2, a part of the apparatus being broken away to better accommodate the view to 10 the sheet of drawing.

Fig. 5 is a view taken on the line 5—5 of Fig. 4.

Fig. 6 is an enlarged detail view of a part of the scraper blade shifting mechanism illustrated in Fig. 4.

Fig. 7 is a plan view of the shifting mechanism taken on line 7—7 of Fig. 4.

Referring more particularly to the drawings, A indicates a hopper for receiving and storing pulverized material such as powdered coal, or the like, the said hopper being provided with feed mechanism, which will be hereinafter described in detail, which mechanism is positioned in suitable compartments or sections of the hopper and which is actuated by suitable driving instrumentalities.

It will be seen from the drawings that the hopper A is substantially funnel-shaped, and opens into a compartment B, which communicates with a lower compartment C, into which the material passes to take its discharge position, it being ejected from this compartment into a suitable combustion chamber, not shown, where it is burned. Suitable means, to be later pointed out in detail, are provided for effecting the discharge. The driving instrumentalities for the feed mechanism whereby the fuel is delivered from the hopper to the discharge means, is housed in compartment D, the discharge means being located in the compartment E.

It will be seen that the hopper A, is provided with a cover 1, having an intake opening 2 through which the hopper A is filled with pulverized material, such as, for example, powdered coal. The opening 2 is surrounded by an annular upstanding flange 3, provided with a cover 4, which is removable, of course, for filling the hopper A. The cover 1 of the hopper A is provided with an opening for receiving the tubular member 5 which defines a central shaft extending vertically substantially through the hopper A. The tube 5 is provided adjacent its upper end with a spacer 7 through which is passed a hollow shaft 8 for effecting adjustment of certain 45 50 55

of the feeding instrumentalities as will be mentioned in greater detail hereinafter.

The lower end of the tube 5 is flared as shown at 9 to receive a truncated conical portion 10a of the feeder plate casting 10. The portion 10a carries the substantially U-shaped stirring arms 11 which are welded or otherwise secured to the portion 10a. An annular groove 12 in the upper end of the conical portion 10a receives the felt or other sealing medium 13, whereby a seal is effected between the shaft 6 and the hopper A. Another seal is effected by the felt 13a inserted in a groove 12a, in the annular flange 10b, which flange is integral with and below the plate 10, 15 the said felt wiping against the surface 27a, of the casting 27 as the feeder plate rotates.

The feeder plate 10, integral with the arms 14 and hub 15, is keyed to the upper end of shaft 16 and rotates therewith. A worm gear 17 having the hub 18 is also keyed to the shaft 16 and is positioned in the compartment D. The shaft 16 has its lower end journaled in the bushing 19 of the bearing 20a, which bearing is integral with the casting 20. The intermediate and upper portions of the shaft 16 are journaled in the bushings 21 and 22 of the upwardly projecting bearing 23, which is integral with the casting 27.

Between the hub 15 of the feeder plate 10 and the bushing 22 of the bearing 23 there is located a thrust bearing 24.

It will be seen that hopper A opens into the compartment B through a port 25 formed in the feeder plate 10. Compartment B is formed of a pair of castings 26 and 27, secured together by bolts 28 having nuts 29 thereon. Between the castings 26 and 27 is a groove in which plate 10 rotates. The casting 27 extends downwardly to form the wall 30 for the compartment C and also the top 31 of the compartment D. The bearing 23 is also an integral part of this same casting.

Between compartments B and C there is the communicating opening 32, discharge of coal through which is controlled by an adjustable deflector plow or scraper blade 33, having an upstanding arm 34 in engagement with the lever 35. The scraper blade 33 is pivotally mounted on a pin 33a positioned in a lug 10c integral with feeder plate casting 10. The annular flange 10b is interrupted to form an opening 10d, through which the scraper blade 33 is positioned and also through which the powdered fuel must pass to be discharged through the central port 32.

The lever 35 terminates in a sleeve 36 around the shaft 8, sleeve 36 being interconnected with the shaft 8 by a pin 37 operating in a special groove 38 in the sleeve 36, whereby vertical movement of the shaft 8 effects adjustment of the blade 33 to vary the feed of powdered coal through the opening 32 into the compartment C. From this compartment the coal is withdrawn by suction created by a fan 39 in the fan compartment E, and thereby ejected from the compartment C through pipe 40 into a suitable burner nozzle 65 adapted to extend into a combustion chamber, not shown.

The tubular shaft 5 serves as an air intake for fan 39, which fan is driven by a suitable motor, not shown, connected to the shaft 41. The motor serves also to drive shaft 16 and feeder plate 10, by means of worm 42, meshing with gear 43, which is fixed to the shaft 43a and on which shaft is fixed a worm 43b, which in turn meshes 75 with gear 17. The shaft 43a is journaled in the

casting 20. Worm 42 is mounted on a shaft 44, which carries a sheave 45, actuated in turn by a V-belt 46, driven by sheave 47 on shaft 41. It will be understood that the motor operates only when a fresh supply of the powdered fuel is 5 needed in the furnace, and the operation of the motor may be governed by a thermostatic control system.

From the above description, it will be seen that actuation of the motor drives the feeder plate 10, the arms 11 attached thereto serving to stir the mass of powdered coal and to prevent the same from becoming caked. The powdered coal falls through port 25 in plate 10 onto the upper surface 27a of casting 27, being distributed over 15 this latter surface by the rotation of plate 10, from which it is swept through port 32 by scraper 33 rotating with shaft 16, since shaft 8 is interconnected with the extension 16a of the shaft 16 through a pin 48 positioned in slot 49 in shaft 8. Therefore, sleeve 36, lever 35, upstanding arm 34, and scraper 33 are rotative with the shaft 16.

As has been previously indicated, the amount of fuel fed through deflector, port 32 is determined by the adjustment of the plow or scraper 25 blade 33. This adjustment must be made with some care, owing to the intense heat developed by the combustion of powdered coal, care being therefore required that excess coal is not delivered into the discharge compartment C, and when the proper adjustment of the blade 33 is obtained for satisfactory operation of the mechanism with a given quantity of fuel, this adjustment need not be disturbed until some change in combustion conditions calls for a new adjustment. This adjustment is effected by the spiral groove 38 and pin 37 in sleeve 36 and shaft 8 respectively as has been previously indicated, acting in conjunction with regulating instrumentalities now to be described.

These regulating instrumentalities include a shifting collar indicated at 50 interconnecting the rotative shaft 8 with lever 51. It will be seen that the collar 50 is provided with lugs 52 which are supported in slots 53 in the end of lever 51, 45 the collar 50 extending under the head 54a connected by a vertical stem to a plug 54 fixed in the end of shaft 8, so that vertical movement may be imparted to the shaft by rocking lever 51 about its pivotal support 55 formed on upstanding arm 56 mounted on the hopper cover 1.

The arc through which lever 51 rocks is determined by the adjustment of the nuts 59 along the threaded rod 57. This rod extends loosely through a boss 58 carried by lever 51, said boss 55 being held by the nuts 59 in its adjusted position. The threaded rod 57 is secured to or is integral with a plunger 60a projecting downwardly into the solenoid 60 mounted on cover 1 of the hopper A. The solenoid 60 is wired to operate with the ignition system of the furnace, that is, while the ignition system is functioning, the solenoid is energized, thereby imparting a downward movement to the rod 57 and also an upward movement to the shaft 8 by means of the lever 51. In Fig. 4 the leads to the solenoid 60 are designated 63 and 64. In Fig. 1 the leads to terminals of the electric spark gap in the burner nozzle 65 are designated 63' and 64'. It should be understood that the electric ignition device 70 comprises a primary winding of a Ruhmkorff coil which is in series with the solenoid 60, and the secondary winding of the Ruhmkorff coil is connected by means of the lead 63', 64' to the terminals of the spark gap shown in Fig. 1. 75

The upward movement of the shaft 8 imparts a clockwise movement to the scraper 33 about its pin 33a as viewed in Fig. 5. Therefore, when the solenoid is energized, the scraper will be moved from its running feed position 61 to the maximum feed position 62. This last mentioned feed position of the scraper will be held until the solenoid is de-energized by the breaking of the ignition circuit, when the scraper will be returned to its running feeding position which is set at a predetermined feed by the nuts 59. A spring 57a is positioned between the upper nut 59 and the boss 58 carried by the arm 51 to protect the mechanism from breakage should the scraper 33 be set to its maximum open position for a running feed.

It should be understood that the screw-threaded rod 57 extends freely through an opening in the boss 58 so that when the solenoid is energized and its plunger pulled down, the rod 57 will compress the spring 57a to transmit movement to the lever 51 and thereby lift the shaft 8, and when this occurs the pin 37 shown in Fig. 6 will move along a vertical straight line. By reason of the pin 37 moving in the slot 38, the arm 35 will be moved in a clockwise direction as viewed in Fig. 5 and this will cause the scraper 33 to be moved from its running position 61 to its starting position 62. If the running position 30 should be set at 62 when the solenoid 60 is de-energized, the spring 57a will protect the mechanism from breakage. This protection is afforded by reason of the fact that when the scraper is in its dotted line position 62 at the time when the solenoid is energized it bears against the inner cylindrical wall of the compartment B, and therefore such cylindrical wall acts as an abutment to prevent downward movement of the shaft 8 when a force is exerted to move downwardly to the right hand end of the lever 51 as viewed in Fig. 4. That is to say, whenever the scraper 33 engages the inner cylindrical wall of the compartment B before the plunger of the solenoid 60 moves down to its full extent, the spring 57a will be compressed against the boss 58 to protect the connections between the latter and the scraper against breakage or undue strain. When the solenoid is de-energized, the tension spring 57a restores the scraper 33 to its running position 61, and the lever 51 will be held in a position predetermined by the adjustments of the nuts 59, 59 as explained above, with the plunger 60a in its upper position.

Therefore, by movement of the nuts along rod 57, the vertical movement imparted to shaft 8 through the lever 51 may be governed as desired, as will be obvious; and each time that the adjustment of nuts 59 is changed, a corresponding change in position of blade 33 is accomplished, a lifting of shaft 8 causing the pin 37 to rotate the sleeve 36 by reason of the spiral grooves 38, 38 therein, so as to swing the blade 33 outwardly, thereby increasing the amount of fuel fed through the port 32.

A lowering of the shaft 8 causes a reverse adjustment of blade 33, thus decreasing the amount of fuel to pass through port 32. As has been previously mentioned also, blade 33 acts on the fuel passed through port 25 to feed the said fuel through port 32 into discharge chamber C whence it is discharged by blower 39. An accurate control of the fuel fed by the mechanism herein described therefore may be accomplished.

The system of control of the operation of the drive for the plate 10 and of the actuation of

solenoid 60 is described in the co-pending application of Earle V. Francis, Ser. No. 652,347, filed January 18, 1933, and it will be understood that the solenoid 60 becomes energized incident to the initiation of each period of fuel supply to the furnace, thereby actuating the blade 33 relative to plate 10 so as to cause the plate to feed additional fuel through port 32 at the start of each combustion period in order that the fuel mixture may be enriched at the time ignition thereof is started. In other words, the action of the solenoid is such that it is energized simultaneously with the operation of the ignition or starting period, so as to throw the blade 33 from position 61 to position 62 and holding the blade in such position during the time the solenoid 60 is energized; and when the solenoid 60 becomes de-energized, spring 57a returns the arm 51 to its original position, which restores blade 33 to its running position 61. During the intervals between energization of the solenoid 60, the shaft 8 simply rotates with shaft 16. It will be understood, of course, that sleeve 36 fits loosely around the shaft 8.

Obviously those skilled in the art may make various changes in the details and arrangement of parts without departing from the spirit and scope of the invention as defined by the claims hereto appended and I wish therefore not to be restricted to the precise construction herein disclosed.

Having thus described and shown an embodiment of my invention, what I desire to have secured by Letters Patent of the United States is:—

1. In a heating apparatus, the combination with a feeding device for pulverized fuel including a hopper for receiving the fuel, of mechanism for feeding the fuel from the hopper into an ejecting position, the said mechanism comprising a rotatable supporting member, agitating means mounted on the supporting member for maintaining a zone of agitated fuel as the supporting member rotates, a feeder plate also mounted on the supporting member and rotative therewith, the said plate having a port therethrough, a second plate below the feeder plate for receiving fuel from the said feeder plate, and also having a port for passing fuel into ejecting position, a scraper associated with the said second plate and rotative with the supporting member for directing fuel through the port of the said second plate, and driving mechanism for the said supporting member and parts carried thereby.

2. Apparatus for burning pulverized fuel comprising the combination with a hopper and means for delivering the fuel from the hopper including feeding mechanism, a shaft, a spiral groove in the shaft and a pin operating in the groove and connecting the feeding mechanism to the shaft, and mechanism for effecting axial displacement of the shaft relative to the hopper for rotatively moving the feeding mechanism incident to displacement of the shaft.

3. In feeding apparatus for pulverized fuel, the combination with a hopper, of a rotatable supporting device, a stationary receiving plate having a delivery port in the center thereof, a feed plate mounted on said support to rotate therewith and provided with a port for passage of material from said hopper to said stationary plate, a pivoted scraper carried by said support in position to move along the upper surface of said stationary plate, and means for adjusting the position of said scraper on its pivot to move the outer

- end of said scraper toward or from said delivery port.
4. A powdered fuel feeder comprising the combination with a fuel hopper for receiving powdered fuel, of feeding mechanism comprising a rotary feed plate and a scraper pivoted to the underside thereof, and means operable axially of the feed plate for adjusting the position of said scraper on its pivot relative to said feed plate.
5. In apparatus for feeding pulverized fuel, the combination with a hopper, of feeding mechanism connected thereto and comprising a rotary feed plate with a scraper adjustably mounted thereon to rotate bodily therewith, and means for adjusting the position of said scraper relative to said feed plate irrespective of the position of the latter relative to said hopper.
6. A powdered fuel feeder comprising the combination with a fuel hopper for receiving powdered fuel, feeding mechanism for delivering fuel from the hopper to a predetermined position, said feeding mechanism comprising a deflector supported for bodily rotation on a predetermined axis, and means operable on said axis and extending eccentrically thereof to said deflector to adjust the position thereof for regulation of the quantity of fuel fed by said feeding mechanism.
7. A powdered fuel feeder comprising the combination with a fuel hopper for receiving powdered fuel, of feeding mechanism operable on a predetermined axis comprising a deflector pivoted eccentrically of said axis, and means operable on said axis and connected to said deflector for adjusting the same on its eccentric pivot.
8. A powdered fuel feeder comprising the combination with a fuel hopper for receiving powdered fuel, of feeding mechanism for feeding fuel from the hopper to a predetermined position, said feeding mechanism being operable on a predetermined axis and comprising a deflector pivoted eccentrically of said axis, and means for adjusting the deflector on its pivot and holding the same in adjusted position for bodily rotation on said axis.
9. A powdered fuel feeder comprising the combination with a fuel hopper for receiving powdered fuel, of feeding mechanism operable on a predetermined axis and comprising a deflector pivoted eccentrically of said axis, means operable longitudinally of said axis for adjusting said deflector on its eccentric pivot, and mechanism co-acting with said adjusting means for effecting bodily rotation of said deflector on said axis while held in adjusted position.
10. Feeding apparatus for pulverized fuel comprising a rotary member mounted on a shaft and a deflector mounted eccentrically of the axis of said shaft, an actuator comprising a coupling to said shaft to compel said actuator to rotate with said shaft but permitting longitudinal movement of said actuator relative to said shaft and means

connected between said actuator and said deflector and comprising pin and spiral slot connections for adjusting the relative position of said actuator and holding the same in adjusted position for bodily rotation with said shaft.

11. Apparatus for feeding pulverized fuel comprising a shaft and a rotary feeding device mounted thereon to rotate therewith, a deflector pivoted to said rotary feeding device eccentrically of said shaft, an actuator coupled to said shaft to rotate therewith but having a longitudinal movement relatively to said shaft, and means comprising a pin and spiral slot connection between said actuator and said eccentrically pivoted deflector for adjusting the latter on its pivot relative to said feeding device and holding the same in adjusted position for bodily rotation with said feeding device and said shaft.

12. In feeding apparatus for comminuted fuel, the combination with a hopper for receiving the fuel, of a rotatable supporting member, a feeder plate mounted on said supporting member to rotate therewith, the said plate having a port extending therethrough, a second plate spaced below said feeder plate in position to receive fuel from said feeder plate through said port therein, said second plate having a port for delivering fuel to ejecting position, a deflector associated with said second plate and mounted to rotate with said supporting member for directing fuel to and through said delivery port, and driving mechanism for the said supporting member and the feed plate and deflector rotatable therewith.

13. Apparatus for feeding pulverized fuel comprising a rotary support, an annular feed plate carried thereby for rotation therewith and having a port for receiving pulverized fuel, a circular bearing for the periphery of said annular feed plate, a stationary receiving plate spaced below said annular feed plate and having a delivery port extending therethrough, a deflector carried by said rotary support for bodily rotation therewith in the space between said plates for directing pulverized fuel passing through said first-named port for delivery to said second-named port.

14. Apparatus for feeding pulverized fuel comprising a rotary device connected to a shaft to rotate on a predetermined axis and a deflector pivoted to said rotary device eccentrically of said axis, an actuator coupled to said rotary device to rotate therewith on said axis but permitting longitudinal movement of said actuator relative to said rotary device, an arm extending radially from said actuator and connected to said deflector, and means operable by longitudinal movement of said actuator relative to said rotary device for adjusting the position of said deflector and holding the same in adjusted position for bodily rotation on said axis.
